UNITED STATES PATENT OFFICE.

JULIUS H. RICHARDS, OF NEWARK, NEW JERSEY, ASSIGNOR TO SPLITDORF ELECTRICAL COMPANY, OF NEWARK, NEW JERSEY.

ENGINE-STARTER.

1,248,549.

Specification of Letters Patent.

Patented Dec. 4, 1917.

Application filed January 15, 1917. Serial No. 142,435.

To all whom it may concern:

Be it known that I, JULIUS H. RICHARDS, a citizen of the United States, residing at Newark, in the county of Essex and State of 5 New Jersey, have invented certain new and useful Improvements in Engine-Starters, of which the following is a specification.

This invention has reference to a starting mechanism for internal combustion engines 10 and the like, such as are commonly used as the motive means for automobiles and other auto-vehicles. In general it involves a mechanism comprising an electric motor receiving its energy from an electric accumulator 15 and is adapted in turn to apply its mechanical effort to some rotatable member driven by the engine, as for instance the flywheel, for the purpose of imparting the initial rotation necessary to the starting of such 20 prime movers.

The invention has as one of its objects the provision of a mechanism for such purposes wherein an electric motor is so adapted that when operated, said motor automatically 25 engages and drives the engine flywheel through the medium of suitable connecting means associated with and operated by the armature of said motor. To the attainment of this automatic engaging feature said invention involves means whereby the armature of the motor, by reason of its own rotation, is placed in a positive driving relationship with the engine at such times as is desirable, and also in a simple, sure, and 30 effective manner.

Another object is to provide a starting system of this class such that after having accomplished its purpose of starting the engine, the driving connection between said 40 engine and the motor is automatically released, whereby said motor becomes inoperative and may be deenergized until it is again desired to be put into operation for the purpose of cranking the engine.

With these and other objects in mind my 45 invention is characterized by an arrangement and operation of elements in which there is attained a device of this character, having the very desirable features of simplicity, surety of action, and relatively low cost of manufacture.

While the present invention involves several of the features and principles of construction shown and described in my prior 50 applications, Serial No. 877,146, filed De-

ber 14, 1914, and Serial No. 41,203, filed July 21, 1915, it is intended as an improvement of the constructions shown therein inasmuch as I have designed and substituted automatic means to take the place of the manually operated engaging means disclosed in said applications, and have in general altered and simplified the present construction as will become more apparent after having considered the following description. 60 65

In the drawing accompanying said description wherein like reference characters are used to identify like parts throughout the several views; Figure 1 is a longitudinal elevation of my improved starting system showing in a conventional manner an electric motor, with the driving devices associated therewith. 70

Fig. 2 shows on an enlarged scale one method of constructing the counterbalancing means for retaining the driving pinion against rotation while the same is being advanced into engagement with the engine member. There is also shown in dotted lines an alternative method of constructing this 80 element. 75

Fig. 3 is a diagrammatic representation illustrating the starting motor, switch, and storage battery electrically connected in circuit. 85

Referring more particularly to the drawing, 1 is the frame of an electric motor which may be of such construction as best adapts it to be suitably mounted in its working relation adjacent the engine flywheel with which it is to coöperate. Secured to the frame 1 is a supporting member 2 which carries one of the motor bearings 3, the other of said bearings 4 being provided as seen at the other end of the 90 motor. In Fig. 1 an armature 5, shown in dotted lines, is suitably arranged within the frame 1 and is mounted upon a shaft 6. Said shaft is provided with a hollow opening extending throughout its entire 100 length and is supported for rotation in the motor bearings 3 and 4. This hollow shaft 6 is adapted to project to a considerable distance beyond one end of the motor and is provided with any suitable number of helical splines 7. At the extreme end of said shaft a portion thereof is reduced in diameter and has a resilient member 8 mounted thereupon and held in place as by means of a collar 22 fixed upon said shaft 110 95 105

110

by a pin 9. Said resilient member consists of a compression spring the free end of which bears against the shoulder formed by the termination of the splines 7 and the 5 other end against said collar 22, and which spring when being mounted in position upon the hollow shaft 6 may, if desirable, be given an initial compression by reason of its said engagement with splines 7. In 10 this manner a more resilient spring may be used in the limited space available and still be capable of offering the sufficient resistance when fully compressed. The function of this spring 8 will later be described. Dis- 15 posed within the hollow armature shaft 6 is a plain shaft or rod 10 which is adapted to move longitudinally back and forth there- 20 in. On the splined end of the said shaft 6 there is mounted a pinion 11 having in- 25 ternal spiral channels cut thereon such that relative rotation of said pinion and the shaft 6 will cause the former to move axially thereupon. Between two adjacent splines 7 is a slot 12 cut through the hol- 30 low shaft 6 and extending spirally around the same at a similar pitch to said splines. A pin 13 passes through the rod 10 and ex- 35 tends at either end through the slots 12 and into the pinion 11. The hole for said pin 40 in the gear 11 is preferably located between two adjacent teeth and consequently the length of this pin must be made such as not to project beyond the roots of said teeth to interfere with their engagement with the 45 engine flywheel. At the other end of the motor the rod 10 is adapted to project at a suitable distance therebeyond and has mounted upon its end a circular disk 14. Said member 14 may be of any suitable 50 material and has a hole 15 near its periphery by means of which the same may be fitted upon the end of the shaft 10. When thus in position a set screw 16 is screwed into the tapped hole 17 to hold said disk 55 from relative rotation with the shaft 10. Being disposed in an eccentric manner upon the rod 10 the disk 14 has its center of gravity disposed considerably below the axis of said rod and thereby its inertia constitutes 60 an impeding agency against the tendency of said shaft to rotate. In the showing of Fig. 2 the dotted lines illustrate that, if desirable, the segmental portions 18 and 19 may be cut away with the result that the 65 center of gravity of said disk 14 is still further lowered below the center of the hole 15, and thereby increases the inertia effect of said disk. It will of course be understood that such factors as diameter, thickness, and 70 material of this counterbalancing member are all subject to change and may be varied at will to secure any desired retarding effect upon the rod 10, for which this member is designed. And while I have shown in 75 the present embodiment that the same is se-

cured upon its shaft 10 by means of a set screw it is apparent that other means may be used, as for instance, a slot and key or by a shrink fit.

Considering now the operation of my 70 starter it will be assumed that the same is mounted in its proper working relationship with some member operated by the engine, as for instance, the flywheel 20. In the drawing, wherein only a portion of said 75 flywheel is shown, the starting motor is at rest with the starting pinion in its normal inoperative position. Upon the switch S being operated to close the electrical circuit through the battery B and motor M the 80 armature 5 thereof and hollow shaft 6 upon which the same is mounted will begin to rotate in the proper direction. Said hollow shaft 6 having mounted thereupon pinion 11 has a tendency to likewise rotate the same 85 therewith. But said pinion being securely pinned to the rod 10, and said rod being retarded by means of the eccentric weight 14 is held against rotation. Thus by rea- 90 son of relative rotation between the gear 11 and hollow shaft 6 the splined engage- 95 ment therebetween causes said pinion and the rod 10 to be advanced longitudinally toward engagement with teeth 21 on fly- 100 wheel member 20. Just before pinion 11 95 has reached its full mesh with the flywheel 20 it engages the spring member 8 and thereby compresses the same until the turning effort of said pinion is sufficient to overcome the resistance of said flywheel and properly crank the engine to which it is attached. In this way the resilient mem- 105 ber 8 serves to receive and absorb the shock of engagement, and as a precaution against damage the elements are so arranged that 105 said pinion 11 reaches its full engagement with said flywheel and the spring 8 is at its maximum compression before the pin 13 has advanced far enough to engage the end of slot 12. In this manner no strain is 110 thrown upon said pin, its only function being to secure the pinion 11 to the rod 10. Upon sufficient charges being drawn into the engine cylinders to start the same under 115 its own power the speed of the flywheel 20 110 immediately picks up and exceeds in value the speed at which it was driven while being cranked by the starting motor. As soon as these conditions occur the pinion 120 115 is rotated relative to hollow shaft 6 and the thrust of the splines 7 is reversed with the result that pinion 11 is moved out of engagement with the engine member and back to its inoperative position. When the 125 above described cycle has been thus com- 120 pleted and the engine has been started switch S, which is preferably situated so as to be conveniently operated by foot or hand, may be released to thereby disconnect the 130 motor from the source of energy B. Should 130

it so happen that, while passing into engagement, a tooth of the pinion 11 should encounter a tooth of the flywheel 20 the eccentric disk 14 would rotate through a sufficient angle to remove said obstruction and permit the proper meshing of said pinion with the engine flywheel.

While the eccentric weight 14 serves to hold the pinion 11 from rotating when the same is passing into engagement with member 20 it also performs a useful function at the time of disengagement. That is, when said pinion passes out of mesh with the flywheel the inertia of the element 14, due to its rotation at this time, keeps the pinion 11 rotating with the shaft 6 until the latter has ceased to turn. This decreases the tendency of pinion 11 to creep back into mesh with flywheel 20 should the operator fail to open the switch S as soon as the engine has started by its own power.

Since it will be apparent that various changes may be made in the construction above described and since a large number of embodiments may be devised all of which come well within the scope of my invention, I wish to have it understood that this specification is merely illustrative thereof and is not to be treated in a limited sense. It is believed that any such changes and alterations are fully covered by the following claims.

Having thus described my invention what I claim is:-

35 1. In a starting apparatus for engines, in combination, an engine driven member, a motor having a hollow shaft, a gear mounted upon said hollow shaft and actuated thereby to automatically engage and drive said engine member, a second shaft within said hollow shaft and means for fastening said gear securely to said second shaft, and an inertia element on the end of said second shaft to prevent the same from rotating, thereby assuring an engagement of said gear with the engine member when said hollow shaft is operated.

2. In a starting apparatus for engines, in combination, an engine driven member, a motor having a hollow shaft, a gear screw threaded thereupon and adapted to be actuated thereby for the purpose of automatically engaging and driving said engine member, a second shaft within said hollow shaft one end of which is rigidly fastened to said gear, an eccentric weight upon the other end of said second shaft serving to hold the same and said gear from rotating, whereby when said hollow shaft is operated said gear is moved into engagement with the engine member.

3. In a starting apparatus for engines, in combination, an engine driven member, a rotatable armature, a hollow shaft for supporting said armature and bearings there-

for, said hollow shaft having an extension at one end, spiral splines on said extension, a gear wheel mounted upon said splines for longitudinal movement relative to said hollow shaft, an inner shaft within the hollow shaft, a slot in said shaft extension substantially parallel to said splines and means passing through said slot for fastening said gear wheel to said inner shaft, and means for holding said inner shaft from rotating whereby when said armature is operated said hollow shaft rotates relative to said inner shaft to carry the gear wheel into engagement with said engine driven member.

4. In a starting apparatus for engines, in combination, an engine driven member, a rotatable armature, a hollow shaft for supporting said armature and bearings therefor, said shaft having an extension at one end, spiral splines on said shaft extension, a slot in said hollow shaft between two of said splines, a gear wheel mounted on said shaft extension, a shaft within said hollow shaft, a pin passing through said gear and inner shaft and adapted to move in said slot, means acting upon said inner shaft to hold the same from rotating whereby when said armature is operated said inner shaft is caused to move longitudinally to carry said gear into engagement with the engine driven member, and means on the end of said hollow shaft for absorbing the shock of said gear as it passes into said engagement.

5. In a starting apparatus for engines, in combination, a rotatable member driven by the engine, a second rotatable member, a driving gear carried by said second rotatable member, a third rotatable member mounted within said second rotatable member, means common to both the driving gear and second rotatable member for moving said gear longitudinally into driving engagement with said engine driven member, means for securely fastening said gear to one end of said third rotatable member, and an eccentrically disposed member upon the other end of said third rotatable member serving to hold the same and said gear from rotating while said gear is passing into said engagement.

6. In a starting apparatus for engines, in combination, an engine driven member, an electric motor having an armature mounted for rotation upon a hollow shaft one end of which shaft projects beyond the end of said motor, bearings for said hollow shaft in the frame of said motor, splines helically arranged about the projecting end of said shaft, through slots in said hollow shaft between adjacent splines and arranged parallel therewith, a driving pinion loosely threaded upon said splines, a second shaft within said hollow shaft, a pin passing through said pinion and slots and said second shaft to fasten said pinion securely to said second

shaft, and an eccentric weight on the end of said second shaft to hold the same from rotating when said hollow shaft is operated, thereby permitting the engagement of said splines with said pinion to move the latter into mesh with said engine driven member.

7. In a starting apparatus for engines, in combination, a rotatable member driven by the engine, an electric motor having an armature mounted upon a hollow shaft, said shaft extending beyond one end of the motor and having spiral splines thereupon, an inner shaft within said hollow shaft adapted to move axially relative thereto, a pinion mounted upon said splines and adapted to move axially thereupon into and out of engagement with said engine member, means for rigidly fastening said pinion to the end of said inner shaft, and a counterbalancing member secured to the other end of said inner shaft, the inertia of said counterbalancing member serving to hold said pinion and inner shaft from turning while said pinion is passing into engagement with the engine member, the inertia of rotation of said counterbalancing member after said pinion has become disengaged from the engine member serving to prevent said pinion from accidentally creeping back into engagement with the engine driven member.

8. In a starting apparatus for engines, in combination, a member driven by the engine, an electric motor having its armature mounted upon a hollow shaft one end of which shaft projects beyond its bearing, a second shaft within said hollow shaft having an extension at either end of said motor and adapted for longitudinal movement relative thereto, a driving gear mounted upon said hollow shaft projection having a screw threaded engagement therewith, a pin securely fastening said gear to one end of said second shaft and a slot in said hollow shaft to accommodate said pin, and an eccentric counterpoise fastened to the other end of said second shaft serving to restrain the same from rotation, whereby when said hollow shaft is rotated said gear by reason of its screw threaded engagement therewith is moved into driving engagement with the engine driven member, said slot serving to permit relative movement between said gear and hollow shaft while said gear is being moved into such engagement, said screw threaded engagement between the gear and said hollow shaft further serving to automatically disconnect said gear from the engine driven member when the engine runs on its own power.

9. In a starting apparatus for engines, in combination, an engine driven member, a motor having an outer and an inner shaft, a gear adapted to engage and drive said engine member, said gear being mounted upon the outer of said shafts but fastened to said

inner shaft, and means on said inner shaft serving to assure an automatic engagement of said gear with the engine member when said outer shaft is operated.

10. In a starting apparatus for engines, in combination, an engine driven member, a motor having a hollow armature shaft, a second shaft within said hollow shaft, a pinion mounted upon said hollow shaft and adapted to automatically engage and disengage said engine member, said pinion being securely fastened to said inner shaft but driven by said hollow shaft, and means acting upon said inner shaft to assure an engagement of said pinion with the engine member when said hollow shaft is operated. 70 75 80

11. In a starting apparatus for engines, in combination, a member driven by the engine, a motor having a hollow armature shaft one end of which projects beyond its bearing, spiral splines upon said shaft projection each of which terminates in a shoulder, a resilient member disposed between said shoulders and a collar upon the end of said hollow shaft, a gear mounted upon said splines and adapted to be actuated thereby to automatically engage and drive said engine member when said hollow shaft is rotated, a second shaft within said hollow shaft, means fastening said gear to said second shaft, and an inertia member on said second shaft serving to hold the gear from rotation while being moved into engagement with said engine member, said resilient member serving to absorb the shock of said engagement. 90 95 100

12. In a starting apparatus for engines, in combination, an engine driven member, a motor having two shafts one within the other, a gear actuated by the outer shaft to automatically engage and drive the engine member, a pin securing said gear to the inner of said shafts, and means on said inner shaft to assure an engagement of the gear with the engine member. 105 110

13. In a starting apparatus for engines, in combination, an engine having a driving gear, an electric motor having an armature, said motor having two shafts one of which operatively carries a gear wheel that is adapted to automatically move into engagement with said engine, and means for assuring such movement comprising an eccentric member fastened to the shaft operatively carrying the gear wheel, the other of said shafts having the motor armature mounted thereupon. 115 120

14. In a starting apparatus for engines, in combination, a rotatable member driven by the engine, an electric motor having its armature in a substantially fixed axial position, a hollow shaft for said motor armature, a second shaft slidably within said hollow shaft, a gear wheel on said second shaft, and means for causing said second 125 130

shaft to move axially to automatically carry said gear into driving engagement with said engine driven member.

15. In a starting apparatus for engines, in combination, an engine driven member, an electric motor having a hollow armature shaft and bearings therefor, a second shaft within said armature shaft, a gear wheel on said armature shaft but operatively connected to the second shaft and means including an eccentric member on the second shaft for moving said second shaft longitudinally, whereby said gear wheel is automatically moved into driving relation with said hollow shaft for the purpose of driving said engine member.

16. In a starting apparatus for engines, in combination, an engine member, a motor shaft carrying means adapted to drive said member, a second shaft operatively connected to said driving means and having eccentric and concentric members thereon co-operating therewith in such a way that said second shaft is moved by the motor shaft to establish a driving relation between said driving means and the engine member.

17. In a starting apparatus for engines, in combination, an engine member, an electric motor having a hollow shaft carrying a gear wheel adapted to drive said engine member, a second shaft slidably supported therewithin and operatively connected to said gear wheel, and means including a counterweight coacting with said second shaft, whereby the same is moved to establish a driving relation between said gear wheel and engine member when said hollow shaft is rotated.

18. In a starting apparatus for engines, in combination, an engine member, a motor having two shafts one within the other, driving means for the engine member drivably carried by the outer shaft but operatively connected to the inner shaft, said inner shaft being weighted so that its center of gravity is out of line with respect to the axis of the outer shaft whereby rotation of the outer shaft causes the inner shaft to move longitudinally to carry the driving means on the outer shaft into engagement with the engine member.

19. In a starting apparatus for engines, in combination, an engine member, a motor having two shafts one within the other, driving means fastened to the inner shaft and adapted to be operatively connected to the engine member said inner shaft having its center of gravity outside its axis of rotation and co-operating with means on the outer shaft to move the driving means into engagement with the engine member when the outer shaft is rotated.

20. In a starting apparatus for engines, in combination, an engine member, a motor having two shafts one within the other, driving means fastened to the inner shaft and adapted to be operatively connected to the engine member, said inner shaft having an inertia device attached thereto and adapted to co-operate with means on the outer shaft to move the driving means into engagement with the engine member when the outer shaft is rotated.

In witness whereof I affix my signature.

JULIUS H. RICHARDS.
